MECHANISM FOR CLEANSING TYPE IN
GALLEYS

Joseph F. Hall, Walpole, and Charles P. Dunn,
Norwood, Mass., assignors to Plimpton Press,
Norwood, Mass., a corporation of Massachusetts

Application April 8, 1938, Serial No. 200,914

4 Claims. (Cl. 15—77)

This invention relates to a mechanism for cleansing a surface or surfaces in a single plane. The invention relates more especially to cleansing which requires the use of a liquid solvent or detergent and to the application of such liquid to a surface to be cleansed by means of a rotating member such as a brush to which liquid is supplied in the form of a fine spray.

More particularly, the invention may be used for removing ink from the inked faces of set-up type, electrotyped plates, foundry forms and the like.

By way of example, the invention is herein-after described as embodied in mechanism for cleansing the inked faces of set-up type in galleyes.

In preparing type for printing, the type which is set up is transferred to galleyes which consist of shallow trays having ledges on both sides and one end. The type is locked in the galley and proofs are taken for the purpose of proof-reading for errors. It is then necessary to remove the ink from the impression faces of the type. When several galleyes of type have to be cleansed, it is a troublesome and time-consuming job. Furthermore, when the type faces are cleaned in the usual manner, inky cleansing liquid runs down between the pieces and lines of type and causes them to stick together.

It is an object of the invention to provide apparatus which will apply sufficient cleansing fluid to the type faces for completely removing the ink but not enough to run down between the pieces and lines of type. This not only avoids sticking of the type but also results in economical use of the cleansing fluid. Another object of the invention is to provide apparatus by which loaded galleyes may be quickly and easily cleansed with a great saving of time or effort. It is a further object of the invention to provide such apparatus with devices to safeguard it against undesirable operation.

For a more complete understanding of the invention, reference may be had to the following description of an embodiment thereof, and to the drawings of which—

Figure 1 is a front elevation of apparatus embodying the invention.

Figure 2 is a perspective view of a galley in which a body of set-up type is locked.

Figure 3 is an end view of the apparatus shown in Figure 1.

Figure 4 is a sectional view, on a larger scale, of a portion of the apparatus shown in Figure 3.

Figure 5 is a section on the line 5—5 of Figure 4.

Figure 6 is a fragmentary elevational view of the trackway for the galleyes.

Figure 7 is a section on the line 7—7 of Figure 6.

Figure 8 is a section similar to Figure 7 but showing the parts in a different position of operation.

Figure 9 is a section on the line 9—9 of Figure 6.

The apparatus includes a main frame 10 on which is mounted an elongated trackway extending horizontally and transversely inclined, i. e. laterally tilted, as indicated in Figure 3, the angle of inclination being preferably about 70° from the horizontal. The trackway comprises essentially a pair of rails 11 and 12, the lower rail 12 having a flange 13 (Figure 4) on its lower edge to support loaded galleyes placed on the trackway. Such galleyes are manually deposited in succession on the right-hand portion of the trackway, being leaned against the rails so that the type will not fall out, and are moved toward the left-hand end by a chain conveyor 14 which passes around a pair of sprocket wheels 16 and 18 and which includes a stretch on the flange 13. Spaced lugs 20 engage the galleyes to ensure positive movement thereof at a predetermined rate when the conveyor is driven. A typical galley is illustrated at 22 in Figure 2, this galley having side ledges 24 and one end ledge 26. The matter or body of type 28 is locked in the lower corner of the galley by suitable furniture indicated at 30. The length of the trackway illustrated on the drawings is somewhat more than twice that of a galley so that the trackway can accommodate two galleyes, one in the starting position and one in the finishing position. Between these two positions is mounted a cleansing member such as a suitable cylindrical brush 32 for brushing the inked faces of the type as the galleyes pass in succession. The brush is mounted on a rotatable shaft 34 journaled in a bearing 35 mounted on the main frame 10. The brush is preferably inclined so that the axis of rotation is parallel to the plane of the trackway 12 but is inclined with respect to the direction of progress of the galley along the track, as indicated in Figure 1, and rotates in a direction contrary to the movement of the galley so that the brushing engagement with the type has a downward component toward the lower edge of the galley. The brush 32 is secured on the end portion of the shaft 34 as by a suitable nut 36, the core 55 of the brush 32 being keyed to a collar 38 mount-

ed on the shaft 34 so that the brush is positively driven.

A common source of power, such as an electric motor 40, may be mounted on a platform 41, carried by the frame 10, to drive both the conveyor 14 and the brush 32. The driving connections for this purpose are illustrated in Figures 1 and 3 and may comprise a shaft 42 connected to the motor 40 through a reducing gear indicated at 44. Mounted on the shaft 42 is a pulley wheel 46 which is connected by suitable belt 48 to a pulley wheel 50 on the shaft 34 to drive the brush 32. Also mounted on the shaft 42 is a sprocket wheel 52 connected by a driving chain 54 to another sprocket wheel 56 mounted on a shaft 58. The shaft 58 also carries a second sprocket wheel 60 which is connected by a suitable chain 62 to a sprocket wheel 64. The latter is mounted on a shaft 66 which drives the sprocket wheel 18 by means of a universal joint 68. The sprocket wheel 18 drives the conveyor 14. The sizes of the foregoing sprocket wheels are selected in such a manner as to reduce the speed of drive so that the galleys are moved past the brush 32 at a suitable rate of speed considerably less than the peripheral speed of rotation of the brush itself.

During the rotation of the brush, a suitable liquid detergent, such as gasoline, benzene or an equivalent, is sprayed thereon to cut the ink on the type and to facilitate the complete removal thereof. To this end, a spray nozzle 70 is provided, this nozzle being supplied with cleansing liquid through a pipe 72 which leads to the nozzle from a suitable receptacle 74. An air pipe 76 also leads to the nozzle from a suitable source of compressed air (not shown). The air is controlled by a valve operated by pressing on a valve stem 78. When the valve is opened, the air blast projects a spray of cleansing liquid along the brush in the manner indicated in Figure 4. The nozzle is preferably adjusted to deliver a very fine spray sufficient to moisten the ends of the bristles of the brush but not enough to deposit an excessive quantity on the type. In this manner, the objectionable infiltration of inky cleansing fluid between the lines and pieces of type is avoided. To confine the liquid spray to the brush 32, the brush is enclosed in a hood 80 which has an opening 82 toward the trackway 12. The brush has tangential contact with the type faces through the opening 82. The hood 80 also has a longitudinal boss 84 thereon which is open as at 86 toward the nozzle 70 to receive the spray from the nozzle. The edge of the hood around the opening 86 is preferably bent in as at 88 (Figure 4) to form a gutter to catch liquid which may collect on and trickle down the interior of the hood and to direct such liquid through a suitable tube 90 to a waste receptacle 91. For the operation of the air valve, a solenoid 92 is mounted on the main frame 10, this solenoid having a movable core 94 supported by a spring 95 and connected through a cord or wire 96 to a rocking lever 98 which presses against the valve stem 78. When the solenoid 92 is energized, the core 94 is pulled down against the force of the spring 95 and the lever 98 is rocked to open the valve and thus to operate the spray. When the solenoid 92 is deenergized, the spray valve closes.

Automatic means for controlling the operation of the motor 40 and the solenoid 92 are provided. Such means include a switch 100 for the motor and a switch 102 for the solenoid. In order to avoid fire hazard through sparking at contacts, switches of the enclosed mercury type are pre-

ferred, such switches being opened and closed by rocking the glass containers within which the mercury is sealed. Thus the switch 100 is controlled by rocking a lever 104. In like manner, the switch 102 is controlled by rocking the lever 106.

According to the present invention, the motor which drives the brush and the galley conveyor is automatically controlled, so that, when a galley is placed on the trackway, the motor automatically starts and continues to operate until the galley has been moved past the brush. To this end, a control mechanism is provided consisting of a bell crank rockably mounted as at 112 behind the trackway, one arm of which bell crank is a trigger 110 adapted to project forward between the rails 11 and 12 and beyond the plane of the trackway, so that, when a galley is placed thereon, it leans against the rails and rocks the trigger 110 to the position illustrated in Figures 7 and 8. The bell crank has a second arm 114 which is connected to the switch lever 104 by an extensible link 116. The link 116 includes a pair of coaxial elements which may telescope, or, as indicated in Figures 7 and 8, may comprise two sections of a rod maintained in alignment by a helical spring 118 which surrounds the sections and tends to draw them together. As a result of this construction, rocking movement of the trigger bell crank in a counter-clockwise direction, as it appears in Figures 7 and 8, results in a positive movement of the switch 100 to the open position. A clockwise rocking of the trigger bell crank causes a pull on the spring 118 which closes the switch 100 unless such closing movement is opposed by sufficient force to extend the spring. In order to avoid opening movement of the switch 100 when the galley moves beyond the trigger 110, a second trigger 120 is provided further along the trackway so that the switch 100 will remain closed until the galley is carried beyond the conveyor 14, the conveyor being then ready to receive another galley. Suitable rollers 122 may be mounted on the rail 12, as shown in Figure 1, to support the leading end of the galley as it moves off the conveyor 14. The triggers 110 and 120 are operatively connected by a connecting rod 126. A spring 128 is provided to pull the triggers toward the open-switch position so that the switch 100 is always open when neither of the triggers is engaged by a galley.

In the usual operation of the mechanism it is intended that, as each galley is delivered along the trackway to a position beyond the conveyor 14, it will be at once removed by the operator so as to make room for the next galley which is being propelled along the trackway past the brush 32. In case the leading galley is not promptly removed, it is desirable to stop the machine before the next galley pushes the leading galley off the delivery end of the track. To avoid this difficulty, an auxiliary control device is provided including a trigger 130 which is mounted on a rocking lever 132 at the extreme delivery end of the trackway, the trigger 130 being in a position to be engaged by the leading end of a galley which has been pushed beyond the brush 32. The lever 132 is connected as by a rod 134 to a bell crank 136 which is pivoted at 138, the other arm of the bell crank being connected through a rod 140 to the switch lever 104. When the trigger 130 is engaged by the leading end of an advancing galley so as to rock the lever 132, the bell crank 136 is thereby rocked as is also the switch lever 104. The rocking of the switch lever is in a

direction to open the switch 100 and thus to stop the motor 40. Hence the rocking of the switch lever is against the tension of the spring 118. This increased tension on the spring 118 tends to rock the trigger 110 in a counter-clockwise direction, and, if the spring tension were sufficiently strong, the trigger 110 might push a galley off the conveyor. To obviate such a possibility, the free end of the rod 134 is slotted as at 142. Within this slot rides a pin 144 on a latch 146, the latch being pressed by a spring 148 so that it tends to swing to a position where it can hook onto a nose 150 on the arm 114. Ordinarily the rod 134 holds the latch 146 in the position shown in Figure 7 so that there is no interference with the movements of the trigger 110. If, however, the trigger 130 is engaged so as to shift the rod 134 toward the left, this permits the latch 146 to catch at once upon the nose 150 so as to prevent counter-clockwise rocking of the trigger 110 when the switch lever 104 is rocked by further movement of the rod 134 to open the switch 100. Thus, when a galley reaches the end of the track 12, the motor which drives the conveyor 14 and the brush 32 is automatically stopped. Removal of the leading galley permits the trigger 130 to be pulled back to normal position by the spring 118, the parts thus resuming the positions illustrated in Figure 7.

It is desirable that cleansing fluid be supplied to the brush only when the brush is actually operating on type. To this end, a dual control for the solenoid 92 is provided, one control being responsive to contact with the galley itself and the other control being operated by contact with type in the galley. Thus the spray operates only during the passage of type past the brush, this being true no matter whether the galley is completely filled or only partly filled with matter. Such control mechanism is illustrated in Figures 3, 6 and 9. The switch lever 106, by which the switch 102 is opened and closed, is operated through a rod 169 which is connected to the end of the lever 162 rockable about a pivot 164. The connections are such that, when the lever 162 is in the position indicated in full lines in Figure 9, the switch 102 is open. When the lever 162 is in the position indicated in dotted lines, the switch is closed and the spray is in operation. Two elements hold the lever 162 in the open-switch position shown in full lines in Figure 9. Both of these elements must be moved out of the way before the switch 102 can be closed. One of these elements is a lever 165 pivoted on the rail 11 as at 166. The lower end portion of this lever 165 engages the high portion of a cam edge 168 on the lever 162 to hold the lever 162 against movement to close the switch 102. When the lever 165 is swung to the full-line position indicated in Figures 6 and 9, it is then opposite the low portion of the cam edge 168 so that it no longer obstructs the rocking of the lever 162 to close the switch 102. The lever 165 is swung by a trigger 170 which is engaged by the upper edge of a galley approaching the brush 32. This trigger is rockable about a pivot 172 and is connected to the lever 165 by any suitable means such as a link or rod 174. When a galley strikes the trigger 170, the lever 165 is thus rocked against the tension of a spring 171 so as to permit the lever 162 to rock in a direction to open the switch 102. A second control is provided, however, which prevents such rocking of the lever 162 until the type to be cleansed has reached the brush 32 so as to prevent premature actuation of the spray

when the galley is only partly filled with type. The second control is in the form of a trigger 180 pivotally mounted as at 182 on the lower rail 12. This trigger is engageable by the type itself and is provided with a nose 184 which is engaged by an end of the lever 162 so as to prevent rocking of the lever until the trigger 180 is rocked by engagement therewith of the type or matter in the galley. Such rocking movement of the trigger 180 is against a suitable spring 186 which tends to restore the trigger 180 to the position shown in Figure 6 when not engaged by type in a galley. When the galley having matter therein is started along the trackway by the conveyor 14, the upper edge of the galley rocks the trigger 170 so as to move the lever 165 out of the way of the lever 162. The body of type in the galley is customarily arranged as shown in Figure 2, that is, in the lower right-hand corner of the galley. Thus, as the galley advances, the type engages the trigger 180 just before it reaches the brush 32. The trigger 180 is rocked to release the lever 162 which thereupon rocks under the influence of a spring 190 (Figure 9) thus closing the switch 102 and starting the operation of the spray 70. This rocking movement of the lever 162 to the position indicated by dotted lines in Figure 9 places the end portion of the lever under the nose 184 of the trigger 180, thus preventing reverse rocking movement of the trigger 180 by the spring 186 until the lever 162 has returned to its full-line position as shown in Figure 9. This is to prevent interruptions in the spray during the passage of the type body past the brush such as might otherwise be caused by gaps or indentations in the lower edge of the type body in the galley, against which the trigger 180 bears. Thus, in operation the engagement of the trigger 170 by the galley conditions the control means so that it is ready to close the switch 102 as soon as it is released by the trigger 180. When the lever 162 is released, it locks the trigger 180 until the galley has passed the trigger 170 and the lever 162 has moved to open the switch 102. Thus the switch 102 is closed when the leading end of the type body engages and rocks the trigger 180, and remains closed until the trailing end of the galley itself passes the trigger 170. The spring 171 thereupon rocks the lever 165, the lower end of which rides along the cam edge 168 and rocks the lever 162 to open the switch 102. The spray is thus stopped and the trigger nose 184 moves into position to lock the lever 162 in open-switch position. Thus the spray operates only when the type to be cleansed is opposite the brush. This avoids spattering of excess liquid on the unoccupied portion of a partly filled galley.

It is evident that various modifications and changes may be made in the embodiment of the invention herein shown and described without departing from the spirit and scope of the invention as set forth in the following claims.

We claim:

1. Apparatus for cleansing type in galleys, comprising a rotatable brush, means for advancing loaded galleys past said brush so that the inked type faces are engaged thereby, means for supplying a liquid detergent to said brush, and automatic control means for said liquid supply including a trigger engageable by type in an advancing galley to cause said supplying means to operate.

2. Apparatus for cleansing type in galleys, comprising a rotatable brush, means for advancing

successive galleys past said brush so that the inked faces of type carried thereby are engaged by the brush, a spray nozzle for spraying detergent liquid onto said brush, a control valve for said spray nozzle, operating means for said valve including a solenoid to open said valve when energized, a normally open control switch for said solenoid, and means engageable by type moving past said brush to maintain said switch closed as long as the brush is in engagement with type.

3. Apparatus for cleansing type in galleys, comprising means for advancing a galley in a predetermined path, means for supplying detergent liquid for cleansing said type, said supply means including a valve, and control means for operating said valve, said control means including a member reciprocable to cause said valve to open and close, a spring tending to move said member toward valve-opening position, a trigger normally locking said member in valve-closing position and engageable by the leading end of said galley to release said member, a second trigger normally locking said member in valve-closing

position and engageable by the leading end of the type body in the galley to release said member, and a second spring operative only when the first said trigger is free from engagement by said galley to move said member to valve-closing position.

4. Apparatus for cleansing type in galleys comprising means for advancing a loaded galley in a predetermined path, a cleansing member located to engage the face of the type at a point of said path, means for supplying detergent liquid to said member, and control means for said supply means including a trigger engageable by a galley and a second trigger engageable by type within the galley, said control means being constructed and arranged to start said supply means in operation when the second trigger is engaged by the type and to stop operation of said supply means when the galley moves out of engagement with the first said trigger.

JOSEPH F. HALL.
CHARLES P. DUNN.
